UNITED STATES PATENT OFFICE

TITUS RUSSELL, OF HOLLAND, MICHIGAN, ASSIGNOR TO HOLLAND FURNACE COMPANY, OF HOLLAND, MICHIGAN

APPARATUS FOR FURNACE CLEANING

Application filed August 24, 1925. Serial No. 52,174.

This invention relates to improved apparatus for furnace cleaning. It is adapted to my improved furnace cleaning methods described in United States Letters Patent No. 1,589,986 and 1,589,987, issued June 22, 1926.

5 The object of the invention is to provide a compact and efficient pneumatic means for cleaning a furnace that can be readily transported on a truck and collect the débris, dust and dirt in an effective manner.

10 Objects pertaining to details and economies of construction and operation of my invention will definitely appear from the detailed description to follow.

15 I accomplish the objects of my invention by the devices and means described in the following specification. The invention is clearly defined and pointed out in the claim.

A structure which is a preferred embodiment of my invention is clearly illustrated in the accompanying drawing forming a part of this application, in which:

20 Fig. 1 is a diagrammatic view of my improved structure organized and connected to clean a furnace.

25 Fig. 2 is a plan view of the cleaner structure appearing in Fig. 1.

Fig. 3 is an enlarged detail rear view of the parts appearing in Fig. 2.

30 Fig. 4 is a detail sectional view of the fan taken on a line 4—4 of Figs. 2 and 3.

In the drawing similar reference numerals indicate similar parts in all of the views.

I will refer to the different parts by their numerals of reference. 1 is a hot air furnace, 2 are the hot air pipes leading therefrom, 3 is the smoke pipe, 4 is the fuel feed for the furnace, 5 is the suction fan, 6 is a suction pipe connected to the intake of the fan and to a nozzle 7 which connects to the frame of the door 4. 8 is a diagrammatic view of a gasoline engine for driving the fan. 9 is a dust collector of the cyclone type carried on a suitable truck along with the fan. This is provided with a hopper bottom 91 leading to a removable dust box or drawer 92, which is removable for emptying.

A diaphragm flange 93 extends over the top of the dust collector with an opening at the center. A dust collector bag 94 is secured to

the top of this collector so that it can be inflated upwardly and collect any fine dust that may be discharged from the cyclone dust collector and effectively prevents the passage of any dust whatever into the atmosphere. The 55 dust bag 94 collapses as indicated in Fig. 1 when the machine is not in operation.

The method of operating my improved structure is perfectly clear. The suction pipe with its nozzle 7 is connected to the door frame of the furnace or other outlet. The fan is operated by driving the motor and sucks all débris from the interior of the furnace, delivering it into the dust collector where the same is separated from the air 60 which passes up and is further filtered by the dust bag.

The device is adapted also to connect to any aperture in a furnace casing and by that means a convenient effective apparatus for 65 carrying on the method of cleaning furnaces and furnace casings, made the subject matter of my concurrent patent applications, is provided.

This apparatus is especially designed to be 70 effective and compact for this purpose, and I desire to claim the same especially for that purpose herein.

Having thus described my invention what I claim as new and desire to secure by Letters 75 Patent is:

A portable suction fan, a suction tube connected to the intake thereof, a portable dust collector of the cyclone type associated with the said fan and connected thereto to receive 80 the débris therefrom and deliver air upwardly at the center, and a balloon-shaped dust bag secured centrally to the top of said dust collector to receive the discharged air and above the cyclone dust collector and disposed 85 to collapse on the top thereof, all coacting as specified.

In witness whereof I have hereunto set my hand.

TITUS RUSSELL. 95
